(57) **CLAIM**

The ornamental design for a blade for a ceiling fan, as shown and described.

DESCRIPTION

FIG. 1 is a bottom plan view of the blade for a ceiling fan in accordance with my design;

FIG. 2 is an enlarged front view of the blade for a ceiling fan in accordance with my design;

FIG. 3 is an enlarged rear view of the blade for a ceiling fan in accordance with my design;

FIG. 4 is an enlarged top plan view of the blade for a ceiling fan in accordance with my design;

FIG. 5 is an enlarged bottom plan view of the blade for a ceiling fan in accordance with my design;

FIG. 6 is an enlarged left elevation view of the blade for a ceiling fan in accordance with my design; and,

FIG. 7 is an enlarged right elevation view of the blade for a ceiling fan in accordance with my design.

The front and rear, left and right elevational views are symmetrical.

The broken line showing of environmental structure in FIG. 1 is for illustrative purposes only and forms no part of the claimed design.
